MULTIPLE SPRING TESTER

Filed Nov. 24, 1950

UNITED STATES PATENT OFFICE

2,614,414

MULTIPLE SPRING TESTER

Robert E. Schafer, Lancaster, and Marlin I. Kreider, Ephrata, Pa., assignors to Hamilton Watch Company, Lancaster, Pa.

Application November 24, 1950, Serial No. 197,368

4 Claims. (Cl. 73—91)

1

This invention relates to an apparatus for life testing a plurality of watch mainsprings.

The object of the invention is to provide an apparatus upon which can be mounted a plurality of watch mainsprings and which in a relatively short time will continually wind and unwind the springs to determine the working life of the spring.

A further object of the present invention is to provide an apparatus for testing the fatigue 10 limit of coil springs, by alternately applying a winding and unwinding action to the springs for a predetermined period, simulating a length of working life of ten years or more.

A further object of the present invention is to provide an apparatus which will simultaneously test a plurality of springs and which will not be affected by the breaking of any of the springs but will continue to test the remaining springs, means being provided to record the point of failure of any one particular spring.

A still further object of the present invention is to provide an apparatus for fatigue testing watch mainsprings which will over a period of approximately five hours give the springs a simulated ten year test.

A further object of the present invention is to provide an apparatus for testing mainsprings which will test a plurality of springs simultaneously while said springs are mounted in the barrel in which they are to be used in the watches.

The invention is illustrated in the accompanying drawing in which:

Figure 1 is a perspective view of the apparatus.

Figure 2 is a detail showing the driving mechanism.

Figure 3 shows an individual holding chuck for one of the springs.

Figure 4 shows the initial winding member for the springs.

Figure 5 is a detail view partly in section showing the means for fastening the cord to the disc.

A base 9 supports an electric motor 10 having reduction gear box 11, a drive shaft 12 carrying a pinion 13 which is in mesh with a large gear 14 supported by an upright plate 15. A stud 16 is carried by the large gear wheel 14 and pivotally supports a rack 17, which is held in mesh with a pinion 18 by a roller 19 mounted between a pair of levers 20 pivoted on the axle 21 of the pinion 18. The axle 21 is supported by upstanding plates 22 (only one of which is shown) and carries a plurality of discs 23. This is the description of conventional driving mechanism and except for supplying the motive power forms no part of the invention.

The discs 23 are formed with a peripheral groove 24 and are keyed to the axle 21 so that the driving pinion 18 will rotate the discs through

2

a complete turn and reverse the direction of rotation for a second complete turn. This oscillation is imparted by motion of the rack 17.

A platform 25 supports a plurality of cylindrical chucks 26 which are mounted for rotation in ball bearings 27. This mounting is housed in a cylindrical casing 28 which is affixed to the platform 25.

The cylindrical surface of each of the chucks 26 is helically grooved at 29 for the reception of a metallic cord 30, while its upper surface is recessed at 31 to receive a mainspring barrel 32. Centrally located in the chuck and within the recess is a hardened pin 33 to support the arbor of the mainspring. This pin is securely fastened to the arbor and rotates therewith, serving as a thrust bearing or endstone for the rounded end of the mainspring arbor. The mainspring arbor is held stationary while the chuck and inserted pin 33 rotates. Three pinions 34 are set into the top of the chuck to engage the teeth 35 of the mainspring barrel, so that the barrel is held stationary with respect to the chuck.

The cord 30 is provided with a hook 36 which is secured to the eye 37 in the discs 23, so that movement of the discs in the direction of the arrow 38 will transmit the motion of the discs to the chuck 26. The reverse motion of the discs 23 will not rewind the cord 30 on the chuck 26 but merely relieves the pull on the cord 30 and permits the wound spring through its unwinding force to rewrap the cord 30 about the chuck 26, thus providing work for the mainspring during its unwinding action.

Secured to the platform and adjacent each chuck base are a plurality of standards 39, each carrying an elongated bearing 40 supporting pistons 41 mounted for vertical sliding movement in said bearings 40. The lower end of the piston 41 is formed with a square hole 42 to receive the square end 43 of the mainspring arbor. The upper end of the piston terminates in a square projection 44 to receive a handle 45 to initially wind the springs to a full wind position before attaching the cords to the oscillating discs. After the springs are manually wound by the handle 45, the pistons 41 are locked from rotation by tightening a split collar 46. Counters 47 adjacent each of the chucks keep an accurate record of the number of times the springs are wound.

In the initial setting the mainspring and its companion barrel and barrel arbor are placed in the circular recess 31 of the chuck, the teeth 48 of the mainspring barrel engaging the pinions 34 which are rigidly set in the chuck 26, thereby securely locking the barrel to the chuck. The piston is moved vertically in the bearing 40 until the square end 43 of the barrel arbor fits in the socket 42 of the piston. Manual rotation of the

piston 41 by the handle 45 winds the spring to complete wind position and the piston is then locked in position by the split collar 46. At the same time the cord which is completely unwound from the chuck is attached to the disc 23 by means of the hook 36 and the eye 37 at a time when the discs are in the position of full wind of the spring. All this is done with the machine stationary for each of the springs. The motor is then started and the first revolution of the discs is in a direction counter to the arrow 38, the tension of the spring rotating the chuck on its bearings 27 to wrap the cord 39 about the chuck constantly maintaining a slight tension on this cord. Further oscillation of the discs 30 alternately winds and unwinds the spring at a point from full wind to $\frac{1}{2}$ unwind which tests the spring as it is used in a watch. The motor through its gears 11 may be geared to run at any particular speed and it has been found running at ten revolutions per minute will produce a test of one hundred years of spring use in approximately fifty hours. If at any time during the test one of the springs breaks, the rotation of the chuck 26 will, of course, cease and the individual counter at that particular chuck will show the number of revolutions at the time of stoppage. The remaining springs, however, continue to be tested, the rewrapped cord 30 dropping from its particular disc when relieved of the tension due to breakage of the spring.

What is claimed is:

1. A multiple mainspring tester comprising a base, a platform mounted on said base, a plurality of chucks rotatably mounted on said platform for supporting and carrying the mainsprings to be tested, an arbor attached to the inner end of each mainspring, means engaging the arbors for an initial manual winding and a subsequent holding of said arbors, means connected to said chucks for alternately unwinding and winding said mainsprings, and means for recording the number of times each mainspring is wound and unwound.

2. A multiple mainspring tester comprising a base, a platform on said base, a plurality of chucks rotatably mounted on said platform for supporting and carrying the mainsprings to be tested, an arbor attached to the inner end of each mainspring, means engaging the arbors for an initial manual winding and a subsequent holding of said arbors, a plurality of oscillating discs, a flexible means connecting each of said discs with each of said chucks to alternately unwind and wind said mainsprings, and means for recording the number of times the mainsprings are wound and unwound.

3. A multiple mainspring tester comprising a base, a platform mounted on said base, a plurality of chucks mounted in ball bearings on said platform for easy rotation, a separate counter associated with each chuck for recording the number of oscillations of said chucks, a plurality of standards, each standard associated with a single chuck, a piston slidably and rotatably mounted in each standard, manual means for turning any one of said pistons, means for lock-

ing said piston against rotary and vertical movement, a plurality of mainspring barrels carried in said chucks, said barrels being connected to and housing the mainsprings to be tested, an arbor carried on the inner end of each of said mainsprings, said arbors terminating in a square end projecting above said mainspring barrel, said longitudinal and rotatable pistons being formed with a square hole for engaging the square end of said arbor, a set of pinions carried on each chuck to receive the winding gear of said mainspring barrel and so hold said barrel stationary with regard to said chuck, a spiral groove formed in the outer surface of each chuck, a flexible cord attached at one end to the chuck and adapted to be housed within said spiral groove, a plurality of discs formed with peripheral grooves mounted for oscillation so that each disc is in line with the edge of each chuck, means for oscillating said discs, the free end of said flexible cord being attached within the peripheral groove of each of said discs, the movement of said discs in one direction rotating said chucks and winding said mainsprings about the stationary arbors, movement of the discs in the other direction releasing the tension on the cord and permitting the mainsprings to unwind and rotate the chucks to rewind the flexible cord in the spiral groove.

4. A multiple mainspring tester comprising a base, a platform mounted on said base, a plurality of chucks mounted in ball bearings on said platform for easy rotation, a plurality of mainspring barrels carrying the mainsprings to be tested, each barrel being securely held in each of said chucks, a spiral groove formed in the face of each of said chucks, a flexible cord wound around each of said chucks and within said spiral groove, an arbor attached to the inner end of each mainspring, means engaging the arbors for initial manual winding and subsequent stationary holding of said arbors, a plurality of discs each formed with a peripheral groove, means for oscillating said discs, the free end of each of said cords being fastened within the peripheral groove of each of said discs, whereby movement of the discs in one direction will wind the mainsprings and movement in the other direction will permit the torque of the mainsprings to back wind the cord on the spiral groove of the chucks, and a separate counter associated with each chuck for recording the number of oscillations of its individual chuck.
